UNITED STATES PATENT OFFICE.

EVERETT WORTHINGTON, OF SAN FRANCISCO, CALIFORNIA, ASSIGNOR TO RADIO PHONO-KRAFTS, OF SAN FRANCISCO, CALIFORNIA, A COMMON-LAW TRUST.

DESIGN FOR A SOUND AMPLIFIER OR SIMILAR ARTICLE.

Application filed August 11, 1924. Serial No. 10,438. Term of patent 14 years.

To all whom it may concern:

Be it known that I, EVERETT WORTHINGTON, a citizen of the United States, and a resident of the city and county of San Francisco, State of California, have invented a new, original, and ornamental Design for a Sound Amplifier or Similar Article, of which the following is a specification, reference being had to the accompanying drawings, forming part thereof.

The figure is a perspective view illustrating my new design.

I claim:

The ornamental design for a sound amplifier or similar article, substantially as shown.

EVERETT WORTHINGTON.
